UNITED STATES PATENT OFFICE.

PAOLO A. PETRUCCI, OF PITTSBURGH, PENNSYLVANIA.

WATER-HEATER FOR BOILERS.

1,346,334.

Specification of Letters Patent. Patented July 13, 1920.

Application filed April 7, 1919. Serial No. 287,958.

To all whom it may concern:

Be it known that I, PAOLO A. PETRUCCI, a subject of the King of Italy, and a resident of Pittsburgh, in the county of Allegheny and State of Pennsylvania, have invented a new and useful Improvement in Water-Heaters for Boilers; and I do hereby declare the following to be a full, clear, and exact description thereof.

10 My invention relates to boilers, and has special reference to water heaters for boilers which are provided with smoke boxes at one end, such as locomotive boilers, etc.

15 The object of my invention is to provide a cheap, simple and efficient water heating device, which can be applied to such form of boilers, will enable the preheating of the water fed to the boiler for use therein, and will provide for a free circulation of the 20 water being fed to said boiler at all times.

25 To these ends my invention consists, generally stated, in the novel arrangement, construction and combination of parts, as hereinafter more specifically set forth and described and particularly pointed out in the claims.

30 To enable others skilled in the art to which my invention appertains to construct and use my improved water heating device 35 for boilers, I will describe the same more fully referring to the accompanying drawings, in which:

Figure 1 is a sectional view of the front end of a locomotive boiler, showing my improved water heating device applied thereto;

Fig. 2 is a cross-section of the same on the line 2-2 Fig. 1, looking in the direction of the arrows and with the spark netting removed;

40 Fig. 3 is a plan view of the upper discharge pipe of the heater and its connections with the coil members;

Fig. 4 is a diagrammatic view showing the arrangement of connections between the 45 coil members and the delivery and discharge pipes;

Fig. 5 shows a horizontal section of a locomotive boiler having another form of my invention applied thereto;

50 Fig. 6 is an enlarged cross-section showing the lower portion of the boiler, and

Fig. 7 is an enlarged view of one of the boiler flues employed in Figs. 5 and 6.

Like symbols of reference herein indicate like parts in each of the figures of the drawings.

As illustrated in Figs. 1, 2 and 3 of the drawings, 1 designates the ordinary form of a locomotive boiler, which is provided with the usual smoke box 2 at its front end and into which lead the smoke flues 3 from the fire box (not shown) at the rear end of the boiler, such flues passing through the usual water space 4 in such boiler, and being supported in the usual front sheet head 5 at the rear end on the smoke box 2. The smoke box 2 is provided with the usual exhaust pot 6 leading up from the bottom of the same for the exhaust steam from the cylinders (not shown), and has the usual 60 exhaust tip or opening 7 at the upper end of the same. The usual smoke stack 8 leads from the smoke box 2, and a spark arrester netting 9 extends from the front end of the bottom plate 10 and at an upward incline 65 toward the front end 2' of the smoke box 70 where it is attached in the usual manner.

The bottom plate 10 is preferably formed of sheet metal and extends from the flue head 5 horizontally toward the front end 2' of the smoke box 2 and around the exhaust pot 6, such netting 9 being attached at its lower end to the front end of such bottom, and such bottom is also provided with the usual damper 11 pivoted therein and adjacent said flue head which is automatically 75 opened when the usual superheating device *a* for the steam is used and the locomotive is working.

Leading from the locomotive tender tank 90 and passing through the usual ejector (not shown) is the water supply pipe 12 which connects with a check valve 13 at one side of the smoke box 2 and with the heater *A*, through the main water delivery pipe 14 95 leading from said pipe 12 into the smoke box and extending across the same. This delivery pipe 14 is secured within any suitable connection 15 on the smoke box 2 at its supply end, and is provided with a flange union 16 at such end, while its opposite end is closed by any suitable cap 17. Above the bottom plate 10 is the diaphragm or sheet plate 18, which is preferably formed of sheet metal and extends vertically up 100 from said bottom plate and out to the sides of the smoke box 2, so that it fills the space in said box above said bottom, plate and back of the inner portion 8' of the stack 8. The heater *A* is positioned on part of the 105 diaphragm sheet 18 and above the bottom plate 10. The delivery pipe 14 is centrally

100

105

110

of the heater A and parallel with and above and below said delivery pipe are the discharge pipes 19 and 20. These pipes 14, 19 and 20 are supported at the front end of the heater A by means of the clamps 22 around the same and connected to vertical brace rods 23 between such pipes. The discharge pipes 19 and 20 connect with the vertical coil members 25 of the heater A, as hereinafter described, and empty into the water space 4 of the boiler 1 by means of the rearwardly extending portions 19' and 20' on said pipes. Valves 24 are placed in the discharge portions 19' and 20' to shut off the water for any purpose desired, such as in the case of a burst pipe in any part of such heater.

The coil members 25 of the heater A are positioned in the smoke box 2 and on each side of the exhaust pot 6 and inner stack portion 8'. These members 25 as shown are sixteen in number, with four to a group and two groups *b* being placed between the pipe 14, 19 and 20 on one side of the smoke box 2, and the other two groups being placed between the said pipes on the other side of said box. The members 25 in each group are placed so that three of such members parallel with each other across the front of and on each side of the smoke box 2, while the fourth or remaining member is placed in the rear of and between the inner stack and its adjacent or intermediate member. Branch pipes 14" connect with the delivery pipe 14 and lead to the rear from said pipe 14 for feeding the water to the rear coil members 25 in each of the groups *b*, and such pipes 14" are closed at their rear ends. Each of the coil members 25 are provided with the inner and outer coil pipes 26 and 27 and each of said coil pipes in the upper groups *b* have a short supply pipe 28 connecting with the same and with the delivery pipe 14 and its branch pipe 14" and at the lower ends of said coils, while each of the coil pipes 26 and 27 in the lower groups *b* have a like short supply pipe 28 connecting with the upper ends of the same and the said delivery pipe and its branch pipe. Branch pipes 19" connected with the discharge pipe 19 and branch pipes 20" connect with the discharge pipe 20, such pipes 19" and 20" leading to the rear from said pipes 19 and 20 and being closed at their rear ends. The coil pipes 26 and 27 in each of the upper groups *b* of the coil members 25 have a short discharge pipe 29 leading from the upper ends of the same into the discharge pipes 19 and 19" and such pipes 26 and 27 in the lower groups *b* of said coil members have a like short discharge pipe 29 leading from the lower ends of the same into the discharge pipe 20 and 20".

In the operation of my improved water heating device, the flame and products of combustion from the fire box in the boiler 1 pass through the smoke flues 3 above the

bottom plate 10 into the smoke box 2, where they are directed downward by the damper 11 and diaphragm 18 into the lower part of said smoke box, while such products passing through the smoke flues below said bottom plate 10 will pass directly into the lower part of said smoke box and combine with those products passing through said damper, so that such products will thus come against the heater A and then pass out the stack. 75 The water for being heated by the heater A passes from the tank through the ejector and check valve 13 by the pipe 12 into the main delivery pipe 14 of the heater and thence into the coil pipes 26 and 27 of the coil members 25 through the branch pipes 14" and connecting pipes 28. The water will thus be heated in pipes 14, 14" and 28 and in the coil pipes 26 and 27 by the products of combustion passing around the same, 85 and the heated water will pass from said coils out through the connecting pipes 29 and branch pipes 19" and 20" into the discharge pipes 19 and 20 and thence into the water space 4 of the boiler 1 through the rear portions 19' and 20' on said discharge pipes, such water being further heated in passing to such water space through said pipes 29, 19" and 20" and the pipes 19 and 20 and their rear portions 19' and 20'. 95

In Figs. 5, 6 and 7 my improved water heating device A is shown where the coil members are placed within two horizontal rows of smoke flues 3 in the lower part of the boiler 1 and below the bottom plate 10, the single pipes 27^a forming the coils of said members extend from the front to the rear of said flues. In such case, the water is taken from the tank through the pipe 12' and ejector directly into the smoke box 2. 100 The main water delivery pipe 14^a and discharge pipes 19^a and 20^a are positioned in the smoke box 2 in front of the flue head 5 and below the bottom plate 10, and such pipe 14^a connects with the lower portions of the coils 27^a in the upper flues 3 and with the upper portions of said coils in the lower flues by means of the connecting pipes 28^a. The upper portions of the coils 27^a in the upper flues 3 and the lower portions of such coils 110 in the lower flues connect with the pipes 19^a and 20^a by means of the connecting pipes 29^a.

In the operation of the heater shown in Figs. 5, 6 and 7, the water to be heated passes through pipe 12 and check valve 13' into the delivery pipe 14^a and thence into the coils 27^a in the upper and lower flues 3 through the pipes 28^a, and after it is heated by the flame and products of combustion it passes from such coils through the connecting pipes 29^a into the discharge pipes 19^a and 20^a and thence into the water space 4 of the boiler 1, such pipes 19^a and 20^a and connecting pipes 28^a and 29^a being also heated by the products of combustion in the 115 120 125 130

smoke box 2 in passing through the same from the smoke flues to the stack 8.

Various other modifications and changes in the design, construction and application 5 of my improved water heating device for boilers may be resorted to, without departing from the spirit of the invention or sacrificing any of its advantages.

It will thus be seen that the use of my improved heating device for boilers will supply hot water to the boiler at almost a boiling point by reason of the products of combustion from the boiler coming directly in contact with such heater in passing through 10 the smoke flues and smoke box to the stack, and such products being all waste products from such boiler no loss of heat from the boiler will be had in the use of the device. The use of the device in the boiler will not 15 permit any loss of steam in the boiler and will save the use of coal or other blasting fuel for the boiler by reason of the water being fed to the water space of the boiler in a highly heated condition, while the use of 20 the heater in supplying hot water instead of cold water to the boiler will also enable the nozzle tip of the exhaust pot to be made large if desired, so that the locomotive will thus burn less fuel, will run faster on the 25 same fuel and with less steam pressure.

It will also be seen that when my improved water heating device is applied to a locomotive boiler, enlarging of the nozzle tip will make the back pressure in the cylinder much less, as the locomotive will not need a strong draft to make a bright fire to heat the water that enters the boiler, as the water is heated in the heater before entering the boiler. With the usual small size nozzle 30 tip used at the present time in locomotive boilers, if my improved heater is applied thereto, the boiler will be popping out steam all the time when the locomotive is in working motion by reason of the heated water 35 entering such boiler instead of the usual cold water, so by enlarging such tip a lighter draft will be created and less fuel will be required, thereby avoiding such continuous popping.

50 It will further be obvious that the coil members of my improved heating device can be positioned at different locations in the boiler and the heater can be applied to any boiler with very little expense and without 55 interfering with the operation of the other parts of the boiler. The coil members of the heater can be used with the larger fire or smoke-flues of the boiler when the super-heater is not used, and can also be used with 60 any of such tubes not used by the super-heater, as well as any smoke flues which are below the super-heater flues.

It will also be obvious that by the arrangement of the groups of coils and their con-

necting pipes, a free circulation of water is 65 created when the water is not fed in the lower and upper groups and discharge pipes of the heater.

What I claim as my invention and desire to secure by Letters Patent is:

70 1. A water heating device for steam boilers having a smoke box and smoke flues opening into said box, said device comprising coil members within said smoke box and arranged in upper and lower groups, a main 75 delivery pipe within said smoke box connected to a source of water supply and with the lower portions of the upper groups and upper portions of the lower groups, and discharge pipes in said smoke box connected to 80 the upper portion of the upper groups and lower portions of the lower groups and leading into the water space of the boiler, said members and pipes adapted to be heated by the products of combustion passing 85 through said smoke flues and smoke box.

2. A water heating device for steam boilers having a smoke box and smoke flues opening into said box, said device comprising coil members within said smoke box arranged in upper and lower groups and having inner and outer coils, a main delivery pipe within said smoke box connected to a source of water supply and with the lower portions of the coils in the upper groups and upper portions of the coils in the lower groups, and discharge pipes in said smoke box connected to the upper portions of the coils in the upper groups and lower portions of the coils in the lower groups and leading 95 into the water space of the boiler, said members and pipes adapted to be heated by the products of combustion passing through 100 said smoke flues and smoke box.

3. A water heating device for steam boilers having a smoke box provided with a stack, exhaust pot and smoke flues opening into the same, said device comprising coil members arranged in upper and lower groups within said smoke box and on each 105 end of said stack and pot, a main delivery pipe within said smoke box connected to a source of water supply and connected to the upper portions of one group and the lower portions of the other group, and discharge 110 pipes in said smoke box and connected to the upper portions of one group and the lower portions of the other group and leading to the water space of the boiler, said members and pipes adapted to be heated by the 115 products of combustion passing through 120 said smoke flues and smoke box.

In testimony whereof I, the said PAOLO A. PETRUCCI, have hereunto set my hand.

PAOLO A. PETRUCCI.
